CLAIM

The ornamental design for a toy sword handle, as shown and described.

DESCRIPTION

FIG. 1 is a perspective view of the design of the present invention for a sword handle, the features of the sword blade shown in broken lines being for illustrative purposes only and forming no part of the claimed design;

FIG. 2 is an enlarged perspective view of the toy sword handle of FIG. 1;

FIG. 3 is a front elevation view thereof;

FIG. 4 is a rear elevation view thereof;

FIG. 5 is a top end view thereof;

FIG. 6 is a bottom end view thereof;

FIG. 7 is a right side elevational view thereof; and,

FIG. 8 is a left side elevational view thereof.

The portions shown in broken lines are for illustrative purposes only and forming no part of the claimed design.
